UNITED STATES PATENT OFFICE.

FRANK NATHANIEL PERCIVAL, OF PHILADELPHIA, PENNSYLVANIA, ASSIGNOR OF
ONE-HALF TO WILLIAM H. SAVERY, OF WILMINGTON, DELAWARE.

CARBURETER.

1,359,837.

Specification of Letters Patent. Patented Nov. 23, 1920.

Application filed December 10, 1917. Serial No. 206,498.

To all whom it may concern:

Be it known that I, FRANK N. PERCIVAL, a citizen of the United States, residing at Philadelphia, in the county of Philadelphia and State of Pennsylvania, have invented certain new and useful Improvements in Carbureters, of which the following is a specification.

This invention relates to improvements in carbureters for internal combustion engines, and particularly to a carbureter designed for carbureting kerosene and other comparatively low grade hydrocarbons, the object of the invention being to provide a carbureter whereby the fuel agent will be thoroughly and effectually atomized and commingled with air to form a reliable, efficient and economical fuel mixture.

A further and important object of my invention is to provide a novel form and construction of fuel feed nozzle whereby increased efficiency in the supply of fuel to the engine is obtained.

The invention consists of the features of construction, combination and arrangement of parts, hereinafter fully described and claimed, reference being had to the accompanying drawings, in which:—

Figure 1 is a view in elevation, partly in section, of a carbureter embodying my invention.

Fig. 2 is a vertical section through the carbureter taken on the line 2—2 of Fig. 1.

Fig. 3 is a detail section on line 3—3 of Fig. 2.

Fig. 4 is a perspective view of the fuel injector or feed nozzle.

Fig. 5 is a detail section on line 5—5 of Fig. 4.

Fig. 6 is a perspective view of the air inlet tube.

In carrying my invention into practice I provide a carbureter comprising a casing 1, the upper portion of which is formed to provide a main mixing or commingling chamber 2, and the lower portion of which is formed to provide a heating chamber 3 suitably partitioned or separated from said mixing chamber. The mixing chamber 2 is provided at its top with an outlet 4 through which the fuel mixture passes to the intake of the engine, while the chamber 3 is provided at its lower end with an inlet 5 suitably connected in practice with a conductor 55 for conveying thereto hot exhaust heat and

gases from the engine, whereby said chamber is heated, said heat and gases exhausting from the heating chamber through an outlet 6.

The carbureter is provided at its base with an air inlet 7 opening horizontally through one side thereof, and this inlet forms the lower horizontal portion of a vapor passage 8 extending through and enclosed by the heating chamber 3 and having an outlet end 9 communicating with the base of the mixing chamber 2 at the side of the carbureter casing opposite the air inlet. The vapor passage 8 extends upwardly and rearwardly from the air inlet to the rear of the mixing or commingling chamber on a curved line, preferably on the arc or segment of a circle, in order that the initial mixture of air and vapor passing therethrough will be given a comparatively long, but unobstructed flow course to adapt it to be thoroughly heated in its travel and also caused to have a cross-current or eddying effect, whereby the air and vapor will be more thoroughly commingled. It will be understood, of course, that as the passage 8 is subjected to the heat of the products of combustion from the engine flowing through the chamber 3, the walls of said passage will be intensely heated with the result of expanding the fluid and promoting atomization of the hydrocarbon and admixture of the air therewith to a highly efficient degree.

Disposed within the horizontal air inlet portion 7 of the passage 8 is an air inlet tube 10 of the Venturi type, said tube 10 having flaring inlet and discharge ends 11 and 12 and a constricted central portion 13. In practice, the tube 10 is detachably secured in position by means of a retaining screw 14, allowing tubes with different sized bores to be interchangeably used, to regulate the quantity of air and hydrocarbon admitted to the vapor passage according to the character of the engine in connection with which the carbureter is used or other conditions to be met. The rear or inner half of the base of this tube 10 is formed with a longitudinally extending slot 15 to permit of the upward passage of a fuel inlet or feed nozzle 16 into the central portion of said tube, and to adapt the tube to be slidably inserted and removed without the necessity of removing the nozzle. The nozzle projects upwardly from the base of the por-

tion 7 of the passage 8 and is provided with a longitudinal feed duct 17 having at its upper end a restricted jet orifice 17' communicating with a discharge slot 18. This slot 5 18 opens laterally through the outer face of the nozzle, and extends horizontally or transversely across the nozzle on its side facing the inlet 11. The slot 18 is V-shaped to provide for the free discharge in extended 10 form of a restricted amount of hydrocarbon from the nozzle, the feed of which hydrocarbon is induced by the suction resulting from the inflow of the air through the Venturi tube around the nozzle, a needle valve 15 19 being provided for cutting off the feed of hydrocarbon when required and regulating the amount of flow as desired. The nozzle is beveled or cut away at an outward and rearward angle at each side of the slot 20 to form V-shaped or flaring grooves 18' which intersect the slot, said grooves providing additional sharp edges against which the fuel impinges to promote and increase the suction feed pull and atomization 25 of the fuel. As stated, the jet orifice 17' faces toward the inlet end 11 of the air tube 10 on a line coincident with a vertical longitudinal line passing through the center of the tube, or parallel with the direction of 30 flow of the column of air. Hence that portion of the column of air striking the central or vertex portion of the wall of the V-shaped slot 15 will be sharply or abruptly divided into two diverging rearwardly traveling 35 streams, jointly operating to produce a depression whereby the fuel is drawn outwardly through the jet orifice and also divided into two corresponding streams. The divided streams of air so produced, together 40 with the fuel streams carried thereby, will also be guided by the beveled or inclined faces 18' and caused to travel rearwardly on diverging lines corresponding to the angles of these faces to a certain degree 45 in rear of the nozzle before the streams commingle. As a result of this action a partial vacuum is induced behind and in the region of the nozzle tending to promote and facilitate the rearward flow of the streams 50 of air and their commingling action when the static pressure in the air tube is reduced on each suction stroke of the engine. Furthermore, an important advantage is obtained by the described form of the slot 18 55 and the provision of the sharp edges at the angles of intersection of the diverging faces 18' with the central vertex portion of the slot and sides of the nozzle, in that these edges not only exert a cutting action on the 60 fuel, whereby its atomization is effected, but break up the streams of air into eddies or cross currents, whereby a thorough admixture of the fuel atoms with the air and distribution of the same more uniformly

throughout the mass of air is secured. Also 65 by arranging the nozzle so that the jet orifice and atomizing surfaces thereof directly face toward the inlet end of the air tube, so as to be diametrically opposed to and medially in the path of the current of inflow. 70 ing air, advantage is taken of the force of the velocity of the air, as well as of the reduction of static pressure of the air on the suction strokes of the piston, to secure the positive feed of a proper proportion of the 75 fuel on each suction stroke of the piston and its impingement with sufficient force against the atomizing surfaces of the nozzle to thoroughly atomize the fuel and thereby prepare it for intimate combination with the air to 80 form the explosive mixture. Furthermore, by the division of the fuel into two streams, which respectively preliminarily commingle with the two streams of air flowing around opposite sides of the nozzle, the fuel is more 85 evenly distributed to the air than if it were preliminarily commingled with the stream of air on one side of the nozzle only, and hence when the two fuel-impregnated streams of air combine with a whirling motion, as they do, in rear of the nozzle, the fuel is more intimately and thoroughly diffused throughout the mass of air. Hence it will be understood that as the fuel is also 90 preliminarily atomized by the cutting action 95 of the angular faces of the nozzle a more even and a finer division of the fuel atoms throughout the air is obtained, with the result that liability of condensation of the liquid fuel is diminished, a more uniform 100 grade of fuel furnished, and consequently greater flexibility of action of the engine obtained. The hydrocarbon will thus be discharged in an atomized condition from the nozzle into the smallest portion of the 105 Venturi tube and will meet the inflowing current of air, the mixture thence flowing upwardly through the passage 8 and finally through the outlet 9 of said passage into the 110 main mixing or commingling chamber 2. 115 On its travel through the passage 8 the oxygenated admixture thus produced is heated by contact with the walls of the tube, resulting in a more thorough admixture of the fuel constituents, as will be readily understood.

The hydrocarbon or hydrocarbons to be supplied to the nozzle may be conducted thereto from any suitable source and in any suitable manner. In the present instance I 120 have shown reservoirs or chambers 20 and 21 suitably provided upon the carbureter casing to respectively contain gasoline as a starting fuel and kerosene or other low grade hydrocarbon as a working fuel. These 125 chambers are provided at their lower ends with inlets 22 and 23 for connection with feed pipes 24 and 25 leading from the source

of supply of the hydrocarbons, and said inlets are controlled by needle valves 26 and 27 governed by floats 28 and 29 arranged within the said chambers 20 and 21, whereby a predetermined quantity of hydrocarbon will be maintained in each chamber. The chambers 20 and 21 are in communication through feed passages 30 and 31, governed by controlling needle valves 32 and 33, with the bore or passage 17 of the nozzle 16, whereby the feed of the two hydrocarbons to the nozzle may be separately or conjointly controlled.

The upper or outlet end 9 of the vapor passage 8 is of conical or tapered form, as shown, and arranged to operate therein is a similar shaped spreader and retarder 34 suitably connected to the lower end of a sliding or reciprocating rod 35, extending at its lower end outwardly through the top of the casing 1 and operatively connected with one arm of an actuating lever 36, whereby the spreader 34 is adapted to be periodically reciprocated. The other arm of the lever 36 is arranged in the path of a cam 37, adjustably mounted, by means of a set screw 38 to vary its time period of action, upon one end of a valve stem 39 extending across the fuel outlet 4, the other end of said stem being provided with a crank arm 40 or the like for connection with some suitable part of the engine mechanism, whereby in the operation of the engine the lever will be periodically moved in one direction to elevate the spreader 34 against the resistance of a spring 41 whereby, during the intervals of operation of the cam, the spreader will be lowered or depressed. Mounted upon the valve stem 39 within the outlet 4 is a throttle valve 42, governing the feed of the fuel from the mixing chamber 2 to the inlet of the engine, said valve being opened upon the elevation of the spreader and closed upon the depression thereof or vice versa. The function of the spreader 34, which is of slightly less diameter than the minimum diameter of the tapered outlet 9 of the passage 8, is to reduce the area of said outlet and provide a constricted annular channel for the flow of the fuel vapor into the chamber 2 and to act as a baffle to force the fuel vapor into contact with the walls of the chamber 8, whereby the fuel vapor will be more intensely heated. The spreader itself also serves as a heating surface in this connection. In the operation of the engine, as stated, the conical spreader is reciprocated and on the opening movement of the valve the spreader is raised in the flaring outlet 9 to gradually increase the area of the constricted channel, and upon the closing of the valve the spreader is depressed to gradually restrict the area of the channel, or vice versa, thus regulating the feed in accordance with the working action of the en-

gine and insuring the heating and preliminary commingling of the air and vapor to a high degree before the final conformation of the fuel charge in the mixing or commingling chamber.

The fuel outlet 4 is disposed centrally at a point between the outlet 9 of the tube 8 and has an auxiliary air inlet 43 disposed at the opposite side of the casing from said outlet 9 and communicating with the base 70 of the mixing chamber 2. This auxiliary air inlet is shown in the form of a tube feed within a threaded opening in the casing and provided with a seat 44 adapted to be engaged by an auxiliary air valve 45, said valve being adapted to open under a predetermined suction force of the engine piston. The valve is slidably mounted upon a guide rod 46 carried by a threaded stem 47 of larger diameter than the rod to form a 85 shoulder 48, said stem being adjustably mounted in the top of the casing and provided with a milled head 49 whereby it may be adjusted to vary the tension of a valve controlling spring 50. This spring 50 is 90 disposed between the valve and the shoulder 48, and normally holds the valve closed except when the suction action of the piston is greater than the closing force of the spring, whereupon the valve will be opened 95 to a greater or less extent to admit more or less air to the interior of the chamber 2. A jam nut 51 is provided for securing the valve stem in adjusted position. The tube 43 may be connected in practice with any 100 source of supply of air, preferably heated air. It will thus be understood that when the engine is working at high speed auxiliary charges of air will be automatically drawn into the mixing chamber 2 for admixture with the carbureted air feeding into the chamber through the passage 8, forming a suitably diluted charge mixture which is drawn through the outlet 4 into the engine cylinder. A port 52 communicates with the 110 mixing chamber through which steam or other moisture may be admitted when it is desired to more thoroughly oxygenate the mixture.

By the provision of a carburetor constructed as above described it will be evident that the thorough atomization of kerosene or other like low grade hydrocarbon fuel may be effected, and this atomized fuel preliminarily combined with air in such a 115 manner as to thoroughly commingle therewith, and that the atomized fuel and air thus commingled will be conducted through a heat passage and heated to such a degree as to secure a higher degree of volatilization 120 of the hydrocarbons and more thorough and intimate mixture of air therewith, the thorough intimate combination of the constituents being additionally promoted by the action of the spreader and agitator 34. As a 130

result, a preliminarily carbureted charge of air will be drawn into a heated or commingling chamber for passage to the motor, which may be diluted or admixed therein with an additional supply of air to vary the quality of the mixture as occasion may require. Kerosene or other low grade fuel may therefore be used in a reliable and effective manner and in such a way as to secure economy in the use thereof. It will, of course, be understood that while the device is primarily designed for the use of kerosene as a working fuel, it may be employed for utilizing other comparatively low grade hydrocarbon fuels or mixtures of high and low grade hydrocarbon fuels with advantage.

Having thus fully described my invention, I claim:

- 20 1. The combination with a carburetor including a casing having an air passage therein, said passage being restricted intermediate the intake and discharge ends thereof, of a fuel inlet nozzle extending radially within the restricted portion of the passage and having its discharge outlet directly facing the intake end of the passage and directly opposed to and disposed medially in the path of the current of the inflowing air, the opposite sides of the nozzle adjacent to the discharge outlet having beveled surfaces diverging from said outlet in the direction of the course of flow of the air.
- 30 2. In a carburetor, a casing having an air and fuel inlet, a Venturi tube disposed in said inlet, and a fuel injection nozzle extending upwardly into said tube and having a jet orifice directly facing the entrance end of the tube and directly opposed to and arranged medially in the path of the inflowing air, said nozzle also having beveled surfaces at opposite sides of said orifice diverging in the direction of flow of the air, said Venturi tube being removable from said air and fuel inlet independently of and without disturbing said nozzle.
- 40 3. In a carburetor, a casing having an air inlet, and a fuel injection nozzle extending upwardly into the air inlet at a point between its entrance and discharge portions, said nozzle being provided in its side facing the entrance portion of the inlet with a transverse slot the walls of which diverge from a central point rearwardly in the direction of flow of the incoming air, and said nozzle having a jet outlet opening into said

slot at the angle of intersection of said diverging walls.

4. In a carburetor, a casing having an air inlet, and a fuel injection nozzle extending upwardly into the air inlet at a point between its entrance and discharge portions, said nozzle being provided in its side facing the entrance portion of the inlet with a transverse V-shaped slot the walls of which diverge from a central point rearwardly in the direction of flow of the incoming air, and said nozzle having a jet outlet opening into said slot at the angle of intersection of said diverging walls. 70

5. In a carburetor, a casing having an air and fuel inlet, a Venturi tube disposed in said inlet, and a fuel injection nozzle extending upwardly into said tube, said nozzle having a jet orifice opening through the side of the nozzle facing the entrance of the air and fuel inlet and directly opposed to and medially in the path of the inflowing air, and said nozzle having beveled surfaces at opposite sides of said orifice diverging in the direction of flow of the air. 75

6. In a carburetor, a casing having an air and fuel inlet, a Venturi tube disposed in said inlet, and a fuel injection nozzle extending into the contracted portion of said tube, said nozzle being provided with a jet outlet and a horizontal, transverse V-shaped discharge outlet formed in its side facing the inlet end of said tube and with the central portion of which said jet outlet communi- 90 cates, said slot having its lateral extremities beveled or inclined rearwardly from said jet outlet on diverging lines.

7. In a carburetor, a casing having an air and fuel inlet, and a fuel discharge nozzle 95 extending into said inlet, said nozzle being provided with a jet outlet and a discharge slot, said slot extending transversely across the nozzle at one side thereof and communicating intermediately with the jet outlet, 100 and having its lateral extremities beveled or sloping on diverging lines toward the opposite side face of the nozzle, said slot being substantially V-shaped, whereby edge surfaces are formed to break up and atomize 105 the flowing particles of fuel.

In testimony whereof I affix my signature in the presence of two witnesses.

FRANK NATHANIEL PERCIVAL.
